GARMENT HANGER

Raymond S. Owen, Chicago, Ill., assignor to Waldorf Paper Products Company, St. Paul, Minn., a corporation of Minnesota

Application December 27, 1948, Serial No. 67,380

2 Claims. (Cl. 223—87)

1

My invention relates to an improvement in garment hangers and deals particularly with a means of attaching garments to the body of the hanger. In the use of garment hangers made of paper or paper board, considerable difficulty has been experienced in attaching skirts or other garments to the cross bar of the hanger. The paper board hanger when completed is stiff and rigid and it has been found virtually impossible to pin a garment to the hanger by ordinary means. As a result it has been necessary to fold the garment over the hanger cross bar and to pin the garment to itself. While this method often forms an acceptable means of retaining the garment in place, it has a tendency to pull the garment out of place and to leave noticeable marks on the garment when it is removed.

A feature of the present invention lies in the provision of a garment hanger formed of paper or fiber board and having a cross bar of inverted U-shaped section provided with spaced apertures through which a pin may extend. These apertures are arranged in pairs which are in spaced relation so as to permit the pointed end of a safety pin to pass through one opening through the garment and pass through the hanger again so that the safety pin may be locked.

A feature of the present invention lies in the simplicity with which the pinning operation may be completed. The apertures are formed through the generally parallel sides of the U-shaped cross bar at a point spaced from, but adjacent, the free lower edges thereof. By holding the pointed end of the safety pin at an angle and sliding the pin point along the inner wall of the hanger, the pointed end of the pin will automatically drop into the hanger apertures and provide an immediate indication when the point of the pin is engaged in an aperture.

The pinning of garments to a hanger is not in itself novel and the use of apertures in the cross bar of the hanger might appear to be an obvious means of permitting such a pinning operation to be accomplished. However, in pinning garments to a hanger cross bar of U-shaped cross section, the location and arrangement of the apertures assumes unusual importance. It is difficult to hold the garment and hanger in such a position that the apertures through which the pin may extend may be viewed during the attaching process. The applicant has found that with very little practice the pinning operation may be accomplished without the necessity of holding the hanger so that the apertures therethrough may be seen. The pointed end of the pin is merely held against the lower edge of one side of the hanger in an up-

2

wardly inclined position and at an acute angle to the inner surface of the other side of the hanger cross bar. While held at this angle the pin point is moved along the hanger cross bar until the pointed end drops into one of the pin apertures. The remaining aperture of each pair is spaced properly so that when pins of a predetermined size are used, the pointed end of the pin will readily pass through the hanger wall after impaling the article being supported.

These and other objects and novel features of my invention will be more clearly and fully set forth in the following specification and claims.

In the drawings forming a part of my specification:

Figure 1 is a front elevational view of a garment hanger showing a garment pinned thereto.

Figure 2 is a sectional view horizontally through the cross bar of the hanger shown in Figure 1, showing the position of the pin at the completion of the pinning operation.

Figure 3 is an elevation view of the hanger cross bar showing the location of the apertures therein.

Figure 4 is a transverse sectional view through the hanger showing the manner in which the pin may be held to locate the pinning apertures in the hanger cross arm.

The hanger A includes a cross arm 10 which is connected at its opposite ends along U-shaped connections 11 and 12 to upwardly and inwardly inclined hanger arms 13 and 14. The end 15 of the hanger arm 13 overlaps with the end 16 of the hanger arm 14 and the arms are held in overlapping relation by a hook 17 of suitable construction. The hook 17 is provided with a hook shaped lower end 19 engageable in registering notches 20 near the free ends of the arms 13 and 14 in the construction illustrated. The specific construction of the hook and supporting means is not of importance in the present invention.

The hanger cross bar 10 is preferably of U-shaped cross section as best illustrated in Figure 4 of the drawings and includes a pair of generally parallel side walls 21 and 22 connected by a flat or rounded upper connecting portion 23. Because of the channel or U-shaped section of the cross bar 10, it is difficult to hold the hanger and garment so that the garment, such as B, may be easily pinned to the cross bar.

A pair of spaced apertures 24 and 25 are formed in each of the side walls 21 and 22 of the cross bar near the end thereof most closely adjacent the connection 11. A similar pair of spaced apertures 26 and 27 are provided in each of the cross bar side walls 21 and 22 near the end thereof most closely adjacent the arm connection 12. All of

these openings 24, 25, 26, and 27 are equally spaced from the lower edges 29 and 30 of the side walls 21 and 22 respectively. The holes of each pair are spaced a distance proper to accommodate the pointed pin shank 31 of a safety pin C.

In attaching a garment B to the cross bar 10 of the hanger A the garment is held against one of the side walls 21 or 22 of the hanger with one hand while a safety pin C is held with its unclasped pointed pin shank 31 against the inner surface of this cross bar wall. The pin shank 31 is held against the lower marginal edge 29 or 30 of the opposite side wall and inclined upwardly. The angle of the pin is such as to hold the pointed end at the elevation of the apertures. As the apertures are of considerably larger diameter than the pin shank 31 some variation of the angle is possible. The pointed end of the shank is held at an acute angle to the inner surface of the cross bar side wall through which it is to extend and the pin is moved rearwardly so that the pointed end thereof will slide readily over the inner surface of the cross bar side wall. When the pointed end of the pin registers with one of the apertures, the point drops into the aperture and the operator is immediately advised that the pin point is in registry with a pinning aperture.

The safety pins C are usually provided with a curved pin shank so that the shank may curve outwardly through the garment and then return to pass through the second aperture of each pair. This operation is also readily accomplished by either of two simple methods. The pin is inserted a desired distance through the first aperture so that the point of the pin would approximately register with the second aperture of the pair and the pin shank pivoted slightly until the point locates the second opening. Alternately the shank of the pin may be inserted through the garment, the pin shank either sliding through the second aperture of the pair or along the hanger surface beyond the aperture. The pin may then be moved parallel to the free edge of the cross bar and retracted slightly until the point of the pin engages in the second aperture of the pair.

I have found that it is possible to easily pin garments to the hanger cross bar after but two or three attempts by even an inexperienced operator. Once the manner of holding the hanger, garment, and pin is learned, the operator can pin the garment to the cross bar on the first attempt. This is of importance as the speed of the pinning operation usually determines whether or not a hanger of the type disclosed will be used for supporting garments which must be pinned thereto. Furthermore, it will be noted

that when pinned to the cross bar the garment is held in fixed relation thereto as the pins can not move any substantial distance longitudinally of the cross bar.

5 In accordance with the patent statutes, I have described the principles of construction and operation of my garment hanger construction, and while I have endeavored to set forth the best embodiment thereof, I desire to have it understood that obvious changes may be made within the scope of the following claims without departing from the spirit of my invention.

I claim:

1. A garment hanger including a cross bar and supporting arms connected to opposite ends thereof, said cross bar being of U-shaped cross section and including opposed sides and a connecting base, the connecting base acting to connect the upper ends of the opposed sides, the sides having free lower edges arranged in generally parallel spaced relationship, one of said sides having a pair of spaced apertures therethrough, said apertures being located in substantially equally spaced relation to the free edge of said one side, and being spaced below the base portion connecting the sides, said apertures being spaced apart longitudinally of the said one side a distance suitable to permit the pin shank of a safety pin to pass through the two apertures of the pair.

2. A garment hanger including a cross bar and supporting arms connected to opposite ends thereof, the cross bar being of inverted U-shaped form including opposed sides and a connecting base, which base is arranged uppermost, one of said sides having a pair of apertures therethrough near each end thereof, the apertures of each pair being longitudinally spaced and at least one aperture of each pair being located equi-distant from the free lower edge of said one side of the cross bar, the spacing between the apertures of each pair being similar and being a distance apart suitable to permit the pin shank of a safety pin to pass through the two apertures of the pair.

RAYMOND S. OWEN.
